Charles R. Searle.

UNITED STATES PATENT OFFICE.

TIMOTHY J. FOLEY, OF NEW YORK, N. Y.

WINDOW-SCREEN.

1,246,410.

Specification of Letters Patent.

Patented Nov. 13, 1917.

Application filed March 27, 1917. Serial No. 157,607.

To all whom it may concern:

Be it known that I, TIMOTHY J. FOLEY, a citizen of the United States, residing in the city of New York, borough and county 5 of Bronx, in the State of New York, have invented a certain new and useful Improvement in Window-Screens, of which the following is a specification.

The invention relates to rolling screens in 10 which the screen is automatically wound upon a spring roller and drawn therefrom to cover the window or other opening, and the object of the invention is to provide a device of this character which shall be 15 simple in construction, easily and economically manufactured, readily installed and removed, and easily operated, and which will be durable and serve efficiently.

The accompanying drawings form a part 20 of this specification and show the device as applied to an ordinary double sash window.

Figure 1 is an interior front view of a window equipped with the invention.

The succeeding figures are on a larger 25 scale.

Fig. 2 is a horizontal section taken approximately on the line 2—2 in Fig. 1.

Fig. 3 is a vertical longitudinal section 30 through the box in which the roller and winding mechanism is mounted, showing these parts in elevation.

Fig. 4 is a corresponding vertical transverse section, taken on the line 4—4 in Fig. 3, and partly in elevation.

Fig. 5 is an elevation of one of the guide 35 strips for the edges of screen, showing the latter in vertical section.

Similar letters of reference indicate the same parts in all the figures.

A is a window frame which may be understood to be of the usual construction having inside beads A¹, outside beads A² and parting strips A³ forming the usual guides for the sashes B and C.

At the top of the frame A in the space 45 between the jambs, beneath the lintel and forward of the inside beads A¹, is detachably secured a portable casing or box D open at the bottom and having closed ends

D¹ D¹ in which the journals E¹ of a roller E are mounted. The inner faces of the ends D¹ D¹ are protected by plates D² D² of metal which with corresponding metal partitions D³ D³ located adjacent thereto form pockets

55 at the ends of the box in which are located volute springs F F each attached at one end

to the box and at the other to the roller or its journal so as to exert its force in the direction to wind the screen G upon the roller in a manner analogous to the usual spring shade-roller.

On each jamb of the window frame forward of the inside bead A¹ is mounted a vertical strip H preferably of metal having a continuous vertical groove h therein and provided at intervals with lugs H¹ receiving screws by which the strip is fastened to the jamb. At suitably spaced intervals on the strip, forward of the groove h, are lateral recesses h¹ arranged to receive the protruding ends of spring actuated bolts G² mounted at opposite ends of a bar G¹ forming the lower edge of the screen, and serving to hold the latter extended.

The ends of the bar G¹ are rabbeted and 75 with the margins of the screen are received and guided in the grooves h and the screen is held at the desired height by engaging the bolts G² in the oppositely located recesses h¹ selected. The bolts slide longitudinally of the bar in housings G³ secured thereon and are forced outwardly by helical springs G⁴ encircling the bolts and lying between the housings. The bolts may be withdrawn by any suitable means. That shown 85 consists of cords J J attached one to the inner end of each bolt, passing through eyes J¹ J¹ near the center of the bar G¹ below which they are joined to form a single cord J² terminating in a ring J³ by which the 90 cord J² may be pulled downwardly and the bolts moved inwardly, practically simultaneously, in opposition to their springs G⁴ and thus disengaged from the strips H to permit the screen to be wound on or unwound from its roller to cover the whole or any desired part of the window or to be wholly received in the box D.

The screen is preferably of woven wire of the required mesh and flexibility but may 100 be of any suitable material, and the strip H may be of wood or other material.

The box D with its roller and screen is 105 portable and is easily installed or removed, and when in place and the screen lowered the device serves efficiently in excluding insects while permitting both sashes to be in any position desired for ventilation, and when the screen is fully raised unobstructed access to the sashes is allowed for cleaning 110 or other operations.

Although the invention is shown as ap-

plied to a double sash window of the vertically sliding type, it will be understood that it will serve with windows of other types and with doors or other openings to be protected.

I claim:

1. In a window screen, the combination of a box located at the top of a window frame between the jambs thereof, plates 10 protecting the inner faces of the ends of said box, partitions in said box adjacent said plates, a roller having its journals mounted in said plates and partitions, and springs on said journals with one end attached to 15 the box and the other to said journals, and a flexible screen adapted to be wound upon said roller.
2. In a window screen, the combination

of a portable box detachably secured in a window frame between the jambs thereof, 20 a roller journaled in said box, volute springs mounted in pockets at the ends of said box and joined to the latter and to said roller, a flexible screen carried by said roller and adapted to be wound thereon by the action 25 of said springs, vertically grooved guides secured to said jambs and receiving the margins of said screen, and having each a series of recesses, a bar at the lower edge of said screen, and bolts on the outer face of the 30 ends of said bar arranged to engage said recesses and hold said screen extended in opposition to the force of said springs.

In testimony that I claim the invention above set forth I affix my signature.

TIMOTHY J. FOLEY.
